(57) **CLAIM**

The ornamental design for a digital camera, as shown and described.

DESCRIPTION

FIG. 1 is a rear, top and right side perspective view of a digital camera showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and,

FIG. 7 is a right side elevational view thereof.

The broken line showing of the digital camera is for the purpose of illustrating environmental subject matter and forms no part of the claimed design.

1 Claim, 4 Drawing Sheets**FIG.1**

FIG.2**FIG.3****FIG.4****FIG.5****FIG.6****FIG.7**
